UNITED STATES PATENT OFFICE.

JOHN P. PADDINGTON, OF NEW YORK, N. Y.

GARMENT HANGER.

Application filed April 4, 1925. Serial No. 20,830.

This invention concerns the provision of a simple and efficient garment hanger. An object is to provide a garment hanger of such material and elements co-operating in such a way that the hanger can be made very cheaply and yet be neat in appearance and strong in use and at the same time so readily collapsible when not in use that it can be packed away in a small space such as a suit-
case or a trunk.

Another object concerns the provision of means whereby various parts of the hanger are firmly held together and are sufficiently strong and properly related as to function effectively as a supporter for garments.

The invention is illustrated in the drawings, of which—

Figure 1 is a perspective view of a hanger;
Fig. 2 is a view of one end of the hanger;

Fig. 3 is a section on the line 3—3 of Fig. 2;

Fig. 4 is a side elevation of a modified form of hanger with a portion broken away; and

Fig. 5 is a section taken through the portion of the hanger to which the supporting hook is connected.

The form of the invention shown in the drawings is a preferred form, although it is understood that modifications in the construction and arrangement of the parts and in the character of the materials used may be adopted without departing from the spirit of the invention as set forth in the appended claims.

The preferred form of the invention shown in the drawings comprises a length of tubular fabric 10 within which is disposed a reinforcing metal member of the form shown in Fig. 3. This metal reinforcing member is formed of a strip of metal 11 which has its longitudinal edges bent over toward each other in the form of a smooth curve, these bent portions being designated by the numerals 12 and 13. By bending the metal strip in this manner it is made much more rigid and strong than if it were flat or were tubular in form. The ends of the fabric 10 are embraced by a metal sleeve 14 simulating in outline the form of the metal strip 11 and having a dependent finger 15 struck from the lower surface of the sleeve 14 and acting as a means for supporting a skirt, there being a sleeve at each end of the tubular fabric 10 and each sleeve having a finger 15 as shown. The sleeves 14 also act

to embrace the ends 16 and 17 of a flat strip of fabric, designated 18, with which a hook 19 is associated. This hook is preferably made of one single piece of wire bent back 60 on itself, with end portions 20 and 21 bent under elevated portions of a plate 22. This plate has free edges which are bent around underneath the fabric 18 and act to hold the plate on the fabric as well as to hold the 65 hook on the plate.

In the form shown in Fig. 4, there is provided an endless tubular fabric 23 a portion of which contains the metal reinforcing member 24 of a shape similar to the member 11 previously described. In this case the ends of the tubular fabric are embraced by the hook plate 22, and in this case the plate also embraces a flexible strip of metal 25 the ends of which project in each direction beyond the hook plate 22 within the tubular fabric 23. This is for the purpose of rendering those portions of the tubular fabric which do not contain the reinforcing bar 24 slightly more rigid than they would be 80 otherwise, so that when the garment hanger is used to support a coat the upper legs of the hanger will be more rigid than otherwise.

By providing the hook plate 22 firmly 85 clamped on to the fabric, I enable it to be definitely positioned with respect to the garment hanger and also to maintain the hook in such relation to the plate that it will not fall out. Furthermore, by providing the 90 tubular reinforcing bar within the fabric, I provide a rigid portion for the hanger on which trousers and other similar articles of apparel can be efficiently hung.

By providing the flexible stiffener strip 95 25 I make the upper limbs of the hanger more rigid and yet provide a hanger which can be readily collapsed when desired. By providing the sleeves 14 on the ends of the fabric I enable two kinds of fabric to be 100 readily connected and also provide means whereby skirts can be hung from the hanger.

What I claim is:—

1. A garment hanger, which includes a tubular fabric and a strip of bent metal contained therein to stiffen the same.

2. A garment hanger, which comprises a tubular portion of fabric, a strip of metal disposed therein to reinforce the same, said strip having its longitudinal edges bent over 110 toward each other in a smooth curve.

3. A garment hanger, which comprises a

tubular portion of fabric, a strip of metal disposed therein to reinforce the same, said strip having its longitudinal edges bent over toward each other in a smooth curve, a metal sleeve of outline similar to the reinforcing strip clamped around the ends of the tubular fabric, a flat strip of fabric having its ends connected beneath said sleeve, and dependent fingers struck from the metal of the sleeve forming skirt hangers.

4. A garment hanger, which comprises a tubular portion of fabric, a strip of metal disposed therein to reinforce the same, said strip having its longitudinal edges bent over toward each other in a smooth curve, a metal sleeve of outline similar to the reinforcing strip clamped around the ends of the tubular

fabric, a flat strip of fabric having its ends connected beneath said sleeve, dependent fingers struck from the metal of the sleeve forming skirt hangers, a hook plate connected to the middle of the flat strip of fabric having its free ends bent around said strip to hold the plate thereon, and a metal hook of bent wire pivotally connected to the plate.

5. A garment hanger which includes a cross bar of tubular fabric and a stiffening strip of bent metal housed therein, shoulder supporting portions connected to the ends of the cross bar, and a hook arranged at the union of the shoulder supporting portions.

JOHN P. PADDINGTON.
